GAUGE AND EJECTOR FOR HEEL SHAPING MACHINES

Edmund C. Butler, St. Louis, Mo., assignor of one-half to Universal Wood Heel Co., St. Louis, Mo., a corporation of Missouri

Application October 13, 1950, Serial No. 189,994

3 Claims. (Cl. 144—278)

1

This invention relates to a gauge and heel ejector for a heel shaping machine and more particularly to an attachment for such a machine which serves as a gauge for properly positioning a heel blank as the blank is set in the shaping machine and acts as an ejector for the heel when the shaped heel is released from the machine.

It is among the objects of the invention to provide an attachment for a heel shaping machine which is actuated by the machine when the latter is operated to engage a heel blank and to release a shaped heel to position the attachment for use as a gauge or stop when a blank is being placed in the machine and to eject the shaped heel from the machine when the machine is operated to release the heel, which can be easily mounted on an existing heel shaping machine with no material modification of the machine construction, which is automatically operated by operation of the machine to engage and release a heel, and which is simple and durable in construction, economical to manufacture, and positive and effective in operation.

Other objects and advantages will become apparent from a consideration of the following description and the appended claims in conjunction with the accompanying drawings, wherein:

Figure 1 is a side elevational view of the upper or head portion of a heel shaping machine with an attachment illustrative of the invention operatively mounted thereon;

Figure 2 is a front elevational view of the machine portion and attachment illustrated in Figure 1;

Figure 3 is a top plan view of the machine portion and attachment;

Figure 4 is a side elevational view of the machine portion and attachment looking at the opposite side from that illustrated in Figure 1;

Figure 5 is an exploded perspective view of one component of the attachment;

Figure 6 is a perspective view of the complementary portion of the attachment;

Figure 7 is a view similar to Figure 2, but showing the parts in a different operative position from that illustrated in Figure 2;

Figure 8 is a view similar to Figures 2 and 7, but showing the parts in a still different operative position; and

Figure 9 is a fragmentary perspective view of a part of the head portion of the heel shaping machine.

With continued reference to the drawings, the heel shaping machine illustrated may be of well

2

known construction, a machine of this character being illustrated and described in Patent No. 2,062,416 granted December 1, 1936 to M. W. Howard, for Heel Turning Machine and assigned to the Pope Machinery Corporation, of Haverhill, Massachusetts.

The machine head illustrated comprises a post 10 mounted in a carriage 11 and supporting a bracket 12 above the carriage. A lower jaw frame 13 is adjustably mounted on the bracket 12 and carries a lower jaw 14 in the form of a flat plate having detents 15 on its upper side for engaging one end surface of a shoe heel blank to be shaped in the machine. A standard 16 is adjustably mounted on the lower jaw frame 13 by suitable means, such as the bolt 17, and pin 18 and an upper jaw frame 19 is pivotally mounted on the standard 16 above the lower jaw frame 13 and carries an upper jaw 20 disposed above and opposed to the lower jaw 14. The upper jaw frame is pivotally secured to the standard by suitable means, such as the pivot bolt 21, for pivotal movement about an axis extending transversely of the standard 16.

A handle 22 is pivotally connected to the standard 16 near one end of the handle by an adjustable pivotal connection including a saddle 23 slidable in slots 24 and 25 provided in the standard near the upper end thereof and adjustably movable in the slots by a hand screw 26 threaded through a nut 27 carried by the standard 16 at the upper end of the standard and a pivot pin 9 extending through registering apertures in the handle near one end thereof and in the opposite ends of the saddle. The hand screw is used to adjust the spacing between the upper and lower jaws 20 and 14 when in heel clamping relationship and the handle is movable about an axis substantially parallel to the axis of pivotal movement of the upper jaw frame 19.

When the handle is in its uppermost position the corner 8 of the handle at the pivoted end of the handle and nearest the upper jaw frame 19 is received in a notch 7 in the upper edge of the upper jaw frame permitting the upper jaw to be displaced upwardly from the lower jaw. When the handle is moved downwardly the corner 8 of the handle is moved out of the notch 7 and onto the adjacent surface of the upper jaw frame forcing the upper jaw downwardly toward the lower jaw to clamp a heel blank between the jaws and releasably locking the upper jaw in clamping position relative to the lower jaw. When the handle is manually moved upwardly releasing the upper jaw, the upper jaw is then raised away

3

from the lower jaw by suitable means, such as the tension spring 27 connected between the upper jaw frame and the standard 16 at the upper end of the latter.

When a heel blank is clamped in proper position between the upper and lower jaws of the machine, the carriage 11 moves the machine head with the blank therein past suitable rotating cutters which shape the heel blank to the desired heel shape in a manner well known to the art. Machines of this character are used principally for shaping wooden high heels and wedge heels for ladies' shoes.

Operation of machines of this character require highly skilled operators since the existing machines provide no means for accurately positioning the heel blank between the jaws of the machine laterally of the jaws, although a guide 28 is usually provided on the lower jaw frame adjacent the inner side of the lower jaw for engaging the wedge end of the heel. Even with the guide 28, great skill and considerable time is required to properly position the heel in the jaws so that the heel will be evenly shaped on both sides by the cutters and will have a symmetrical shape with no flat areas.

With the existing machines it is also necessary for the operator to manually remove the finished heel from the machine before he can insert a new blank between the machine jaws. This is also a time consuming operation which tends to reduce the productive capacity of the machine.

Means are provided for assisting the operator in rapidly positioning the blank in the correct position between the jaws of the machine and for automatically ejecting the finished heel from the machine when the jaws are relatively moved to release the heel.

A bar 30 is pivotally mounted intermediate its length on one side of the standard 16 near the upper end of the standard by a pivot bolt 31 for rocking movements about an axis substantially parallel to the axis of movement of the upper jaw frame 19 and the handle 22. This bar has near one end a longitudinally extending slot 32 and a pin 33 projects outwardly from the adjacent side of the handle 22 and is received in the slot 32 to rock the bar about the pivot bolt 31 when the handle is raised and lowered to release and engage a shoe heel between the upper and lower jaws of the machine.

A bracket 34 of channel shaped cross section is secured to the bar 30 near the end of the bar remote from the slot 32 and is disposed substantially perpendicular to the bar, extending outwardly of the upper edge of the bar remote from the upper jaw frame 19. This bracket provides spaced apart flanges or legs and an arm 35 of channel shaped cross section is received in the bracket 34 and is pivotally connected to the bracket near the upper end of the arm by a pivot pin 36 extending through registering apertures provided in the bracket legs near the upper or outer end of the bracket and in the arm 35.

A flat, rectangular head 37 is provided on the upper end of the arm 35 and extends from the arm in a direction past the bracket 34 and bar 30 and a tip or pad 38 of stiff, resilient material, such as vulcanized rubber or synthetic resin plastic, is secured to the arm 35 near its lower end and extends downwardly below the lower end of the arm.

A U-shaped bracket 39 is disposed at the side of the bar 30 to which the bracket 34 is attached

and is secured at its opposite ends to the bar 30 at respectively opposite sides of the bracket 34 and extends around the bracket and the arm 35.

A tension spring 40 is secured at one end to the head 37 at a location spaced from the adjacent end of the arm 35 and is connected at its other end to the bar 30 at the side of the latter remote from the bracket 34 by a suitable screw or pin 41. This spring acts to resiliently rock the arm 35 about the pivot pin 36 in a direction to move the gauge tip 38 carried by the arm away from the adjacent sides of the jaws 14 and 20 of the machine. An adjusting screw 42 is threaded through a tapped hole 43 in the bracket 39 and bears at its inner end against the adjacent side of the arm 35 at a location spaced from the pivot pin 36 to limit movement of the gauge tip away from the jaws of the machine so that the gauge tip will be rigidly held in proper position relative to the jaws when a heel blank is being placed between the jaws to properly position the heel blank relative to the jaws.

A second bar 45 is rigidly secured to the standard 16 at the side of the latter remote from the bar 30 and projects outwardly from the standard above the upper jaw 20 of the machine. At its end remote from the standard, this bar is provided with a socket 46 having two spaced apart end walls 47 and 48 and a bottom wall 49. A U-shaped roller carriage 50 is pivotally mounted in the socket 46 by a pivot pin 51 extending through registering apertures in the end walls of the socket and in the intermediate or bight portion of the roller carriage and a roller 52 is disposed between the legs of the carriage and journaled on an axle pin 53 extending coaxially through the roller and through registering apertures in the carriage legs near the outer ends of such legs.

The roller 52 is positioned in the path of the adjacent edge of the head 37 on arm 35 and is supported by the bottom wall of the socket 46 in a substantially horizontal position beyond which it cannot move as the head moves downwardly past the roller. The roller and carriage can, however, pivot upwardly when the head moves upwardly past the roller so that the head can pass the roller in an upwardly direction without movement of the head.

Operation

With the above described attachment in place on the heel shaping machine, and assuming that the handle 22 is in its uppermost position separating the jaws 14 and 20, a heel blank, as illustrated in Figure 7 and indicated at 55, is placed between the upper and lower jaws of the machine. This blank is generally rectangular in shape, having flat, substantially parallel side walls and an end wall disposed outwardly of the jaws and substantially perpendicular to the side walls. With the handle 22 in this upper position, the bar 30 will be swung about the pivot bolt 31 to bring the gauge tip 38 opposite the space between the upper and lower jaws of the machine and the head 37 on the arm 35 will be disposed below the roller 52. Under these conditions the arm will be moved by spring 40 to its limiting position against the inner end of screw 42 and the gauge tip will be held in proper position so that when the adjacent side of the heel blank is brought against the gauge tip with the wedge end of the blank against the guide 28, the heel will be properly located between the jaws of the machine. This greatly facilitates proper positioning of the blank between the jaws, and when

the blank has been properly placed with one side against the adjacent side of the gauge tip 38, the handle 22 is moved downwardly to move the upper jaw 20 toward the lower jaw 14 and clamp the blank between these jaws. As the handle is moved downwardly the bar 30 is rocked about the pivot bolt 31, raising the arm 35. As the head 37 passes the roller 52, the roller and carriage 50 are raised out of the way of the head so that the head passes the roller without movement of the head or the arm 35 relative to the bar 30. When the handle has been pressed downwardly to its limiting downward position in which it locks the upper jaw in clamping relationship to the lower jaw, the gauge tip will have been raised well above the upper jaw frame 19, as is particularly illustrated in Figures 1, 2 and 4, so that it is not in the way of the rotary cutters as these cutters engage the heel blank to shape the heel.

The machine carriage 11 is now moved to bring the heel blank into engagement with the rotary cutters to shape the heel and, after the heel has been shaped, the carriage and the machine head are returned to the loading and unloading position in which the blank is spaced from the cutters. The handle 22 is now manually raised to release the upper jaw 20 from the shaped heel, the upper jaw, upon release by the handle, being moved away from the heel by the tension spring 27. As the handle is raised the bar 30 is rocked about the pivot screw 31 to lower the arm 35. At the time at which the lower end of the gauge tip 38 is approximately half way between the upper and lower jaws of the machine, the head 37 engages the roller 52, the carriage 50 having been returned by gravity to its substantially horizontal position. As the roller cannot now move out of the way of the head, the head will be forced away from the bar 45 and the gauge tip 38 will be kicked inwardly toward the heel resting upon the lower jaw 14 and will move the heel off of the lower jaw, thereby ejecting the heel from the machine. As downward movement of the handle is continued, the head 37 passes below the roller 52 and the gauge tip 38 is returned by spring 40 to its gauging position at which it enables the operator to properly position a new blank between the jaws of the machine.

The attachment of the present invention thus materially increases the productive capacity of the machine by assisting the operator in properly positioning a new blank between the the jaws of the machine and in automatically ejecting a shaped heel from the machine at the termination of the heel shaping operation.

The invention may be embodied in other specific forms without departing from the spirit or essential characteristics thereof. The present embodiment is, therefore, to be considered in all respects as illustrative and not restrictive, the scope of the invention being indicated by the appended claims, rather than by the foregoing description, and all changes which come within the meaning and range of equivalency of the claims are, therefore, intended to be embraced therein.

What is claimed is:

1. In combination with a heel shaping machine having a lower jaw frame, a lower jaw carried by said frame, a standard adjustably secured to said frame, an upper jaw frame pivotally mounted on said standard, an upper jaw carried by said upper jaw frame in opposition to said lower jaw, and a handle pivotally mounted on said standard and engaging said upper jaw frame to releasably lock said upper jaw in position relative to said lower

jaw to clamp a heel blank between said jaws and to release said upper jaw frame to free a heel from engagement by said jaws, a bar pivotally mounted intermediate its length on said standard and having a longitudinally extending slot near one end, a pin on said handle received in said slot to impart rocking movement to said bar when said handle is moved to move said upper jaw relative to said lower jaw, said bar, said handle and said upper jaw frame being movable about substantially parallel axes, a laterally projecting bracket on said bar near the other end of the latter, an arm pivotally mounted near one end on said bracket for rocking movement about an axis substantially at right angles to the axis of rocking movement of said bar and extending substantially perpendicularly of said bar from said bracket toward said lower jaw, a flat head on said one end and a gauge tip on the other end of said arm, spring means acting between said bar and said arm resiliently urging said gauge tip away from said jaws, adjustable stop means acting between said bar and said arm limiting spring induced movement of said arm to a position relative to said bar at which said gauge tip is properly located relative to said jaws to accurately position a heel blank between the jaws as said upper jaw is moved toward said lower jaw, a second bar rigidly secured at one end to said standard and having a socket at its other end, a roller carriage pivotally mounted in said socket for pivotal movement about an axis substantially perpendicular to the axis of movement of the first mentioned bar, and a roller carried by said carriage in the path of the adjacent edge of said head, said socket limiting pivotal movement of said roller carriage to an angle of approximately 90 degrees so that said roller will move said head in a direction to force said gauge tip toward said jaws and eject a heel from between the latter as said upper jaw is released by said handle for movement away from said lower jaw but will ride over said head without moving the latter when said handle is moved to force said upper jaw toward said lower jaw to clamp a heel blank between said jaws.

2. In combination with a heel shaping machine having a first jaw, means supporting said first jaw in heel carrying position, a standard carried by the jaw supporting means, a second jaw pivotally carried by said standard in opposition to said first jaw for movement toward and away from the latter, and a handle pivotally carried by said standard for manual movement in one direction to lock said second jaw in heel clamping position relative to said first jaw and in the opposite direction to release said second jaw for freeing a heel from between said jaws, a bar pivotally mounted on said standard and movable by said handle, an arm pivotally mounted on said bar, a gauge tip carried by said arm at a location spaced from said bar and movable by the latter to a location opposite the space between said jaws when said handle is moved to its jaw releasing position and to a location spaced from said jaws when said handle is moved to its jaw locking position, spring means acting between said bar and said arm resiliently urging said gauge tip laterally away from said jaws, adjustable stop means acting between said bar and said arm limiting spring induced movement of said gauge tip to a location at which said gauge tip constitutes a guide for accurately positioning a heel blank between said jaws, a projection on the end of said arm remote

from said tip and extending from the side of said arm adjacent said standard, and a body carried by said standard and engaging said projection at the edge of the latter remote from said arm as said handle is moved toward its jaw releasing position to force said gauge tip against a heel disposed between said jaws and eject such heel from between the jaws when said second jaw is released by said handle.

3. In combination with a heel shaping machine having a first jaw, means supporting said first jaw in heel carrying position, a standard carried by the jaw supporting means, a second jaw pivotally carried by said standard in opposition to said first jaw for movement toward and away from the latter, and a handle pivotally carried by said standard for manual movement in one direction to lock said first jaw in heel clamping position relative to said first jaw and in the opposite direction to free said second jaw for releasing a heel from between said jaws, a bar pivotally mounted on said standard and movable by said handle, an arm pivotally mounted on said bar, a gauge tip carried by said arm at a location spaced

5
10
15
20

from said bar and movable by the latter to a location opposite the space between said jaws when said handle is moved to its jaw releasing position and to a location spaced from said jaws when said handle is moved to its jaw locking position, spring means connected between said bar and said arm urging said gauge tip outwardly of the space between said jaws, adjustable means carried by said bar and engaging said arm to limit movement of the latter by said spring means, and means carried by said standard and engaging said arm as said handle is moved to its heel releasing position for forcing said gauge tip against a heel disposed between said jaws to automatically eject the heel from between the jaws.
